MULTIPLE PAN

Adrien L. Langel, Chicago, Ill., assignor to Chicago Metallic Manufacturing Company, Chicago, Ill., a corporation of Illinois

Application January 5, 1938, Serial No. 183,485

10 Claims. (Cl. 53—6)

The present invention relates to baking pans of the multiple type in which a plurality of metal receptacles are mounted together by means of a metal framework so that the plurality of receptacles may be placed within and removed from the oven and handled as a single unit.

The invention is embodied in a multiple pan of the type described, wherein a plurality of receptacles are connected together by means of end plates to which the individual receptacles are secured, and cross bars connecting the end bars between the receptacles, the cross bars being also directly connected to the receptacles. Protector plates are provided at the opposite ends of a series of receptacles, as is common in the art. In this multiple pan structure the present invention provides means on the end plates whereby the pans may be stacked one upon another in stable position with the receptacles nested, but out of contact with each other, so that the interior surfaces will not be marred by the exteriors of the superimposed receptacles.

The multiple pan structure embodying the invention provides also a novel cross bar construction and end bar construction by which stronger and more satisfactory connections are obtained in assembling the several receptacles with the end bars and cross bars.

The features and advantages of the invention will appear more fully from the following description, reference being had to the accompanying drawings wherein a preferred form of the invention is shown.

In the drawings, Fig. 1 is a fragmentary plan view of a multiple pan at an intermediate stage in its manufacture, showing one receptacle completely attached to the supporting end bars and cross bars, with the adjacent receptacle omitted to illustrate the initial construction of the end bars and cross bars.

Fig. 2 is a view in side elevation of the structure shown in Fig. 1, with fragmentary portions of a second pan assembly shown by dotted lines in nesting relation.

Fig. 3 is a fragmentary sectional view taken on the line 3—3 of Fig. 1.

Fig. 4 is an enlarged fragmentary sectional view taken on the line 4—4 of Fig. 2.

Fig. 5 is a sectional view taken on the line 5—5 of Fig. 2.

Fig. 6 is a sectional view taken on the line 6—6 of Fig. 2.

Fig. 7 is a perspective view of one of the parts of the cross bar.

Fig. 8 is a fragmentary perspective view of a

portion of the end bar which is to be connected with the cross bar shown in Fig. 7, and

Fig. 9 is a sectional view taken on the same line as Fig. 3, showing a slightly modified form of the cross bar construction.

Referring now to the drawings, the invention is embodied in a multiple pan which comprises a plurality of metal receptacles 10 that are secured in a framework composed of end bars 11 and 12 and cross bars 13 and 14. The receptacles 10 are the usual rectangular shape, having side panels 15 and 16 and end panels 17 and 18. The receptacles 10 have folded sections 19 and 20 at the ends, the sections being folded over the end panels of the receptacle in the usual manner. Protector plates 21 are provided across the outer side faces of the end pans at the opposite ends of a series of receptacles in the usual manner, having their end portions bent at an angle about the corners of the end pans. The end bars 11 and 12 are extended beneath the protector plates 21, as shown at 22 in Fig. 2, and are welded thereto. Each end bar 11 and 12 also has an inwardly pressed offset portion 23 for each receptacle 10, which offset portion is adapted to fit in between 25 the folded over sections 19 and 20 of the receptacle.

Each end bar 11 and 12 is constructed as shown best in Figs. 5, 6 and 8 by folding a strip of metal 24 upon itself to form a double thickness thereof. One edge 25 of the strip 24 projects beyond the other edge 26 and is curled toward the other edge 26 slightly in the formation of the end bar. Also, midway between the offset portions 23, each end bar has a tongue 27 punched out of the inner wall 28 and turned down in the plane of the outer wall 29 of the end bar, the edge portions of the tongue 27 being bent over on the body of the tongue as shown at 30 in Figs. 2 and 6 to provide a smooth contour around the periphery of the tongue 27. The function of the tongue 27 is to provide a guiding and stabilizing element which, when one multiple pan unit is stacked upon another, will fit between the rims of adjacent receptacles upon the subjacent pan unit, thus locating the stacked units and preventing the outside surfaces of the receptacles in the superposed unit from engaging and marring the inner surfaces of the receptacles. The inner wall 28 of the end bar is split directly over the center line 50 of the tongue 27 down a short distance below the top level of the edge 26, and lugs 31 and 32 are turned inwardly as shown best in Fig. 8. The outer wall 29 is cut out as shown at 33, to provide a recess in the upper edge 26 thereof which is 55

somewhat wider than the distance between the lugs 31 and 32. The function of the lugs 31 and 32 is to cooperate with certain portions of the cross bars such as 13 and 14 in interconnecting the cross bars with the end bars.

As shown best in Figs. 1, 3 and 7, the cross bars are made up of two rectangular frames 34 and 35, placed end to end between adjacent receptacles and connecting one end bar 11 to the opposite end bar 12. The adjacent ends of the frames 34 and 35 are tied together by a cross piece 36 upon the frame 35 and a cross piece 37 on the frame 34. The cross piece 37, shown best in Fig. 3, has a portion 38 bent over to form a hook 15 which fits over the cross piece 36. Each of the frames 34 and 35 in the unassembled form as shown in Fig. 7 has its side portions 39 and 40 curved inwardly at the top edge to facilitate the curling of the receptacle and this top edge together in the assembly operation carried out later. The side portions 39 and 40 have seats 41 and 42 formed by pressing a portion of the side piece inwardly, and these seats are adapted to receive the free ends of the lugs 31 and 32 in the manner 20 shown in Figs. 5 and 6. The side pieces 39 and 40 are cut diagonally across the seats 41 and 42 and extended beyond the seats where they are bent toward each other to provide flanges 43 and 44 which abut the end bars and are secured there- 25 to by welding. It will be noted from an examination of Figs. 5 and 6 that the flanges 43 and 44 lie below the level of the lugs 31 and 32 and fit flatly against the inner wall 28 of the end bar.

Before the receptacles are assembled with the 30 end bars and cross bars, these elements of the cross bars are connected together by securing the flanges 43 and 44 to the end bars. A receptacle is then placed within each rectangular area bounded by the cross bars 13 and 14 and the end bars 11 and 12. The receptacles then have their upper edges 45 curled outwardly and downwardly over the upper edges of the side portions 39 and 40 and the upper edges 25 of the end bars. The upper edges of the lugs 31 and 32 being also disposed within and forming a part of the periphery of the receptacle receiving framework are curled over with the top edge of the receptacle. The showing in Fig. 4 illustrates the manner in which the top edge 25 of the end bar is curled over the top edge 26. It will also be noted that the top edge 45 of the receptacle 10 is curled around and turned up inside the edge 25.

Referring now to Fig. 9, in this form of the invention the cross bars are composed of two rectangular frames 34' and 35' which are identical with the rectangular frame shown in Fig. 7. A rectangular frame 46 is interposed between the frames 34' and 35' and is connected thereto by cross pieces 47 and 48 on the frame 46 and hooked portions 49 and 50 on the frames 34' and 35'. While the frames 34 and 35 and the frames 34' and 35' have been described as rectangular frames, it is evident that they do not form a closed rectangle because the flanges 43 and 44 are separated at their inner ends by a narrow space. Therefore, the term "rectangular flange" as used herein should not be considered as limited to a closed rectangle.

While the preferred embodiment of the invention has been shown and described, it is to be understood that it is capable of many modifications. Changes, therefore, in the construction and arrangement may be made without departing from the spirit and scope of the invention 75 as disclosed in the appended claims in which it

is my intention to claim all novelty inherent in the invention as broadly as possible in view of the prior art.

Having thus described my invention, what I claim as new, and desire to secure by Letters 5 Patent is:

1. In a multiple pan, the combination of a plurality of spaced receptacles with end bars and cross bars connected to said receptacles and to each other, said end bars having lugs extending 10 inwardly toward each other and between said receptacles, said cross bars being provided with seat portions having face to face engagement with said lugs and provided with flanges having face to face engagement with the end bars and 15 fixed thereto.

2. In a multiple pan, the combination of a plurality of spaced receptacles with end bars and cross bars connected to said receptacles and to each other, said cross bars comprising end 20 to end rectangular frames having their adjacent ends connected and their side strips fixed to the adjacent receptacles.

3. In a multiple pan, the combination of a plurality of spaced receptacles with end bars 25 and cross bars connected to said receptacles and to each other, said cross bars comprising end to end rectangular frames having their adjacent ends connected and their side strips fixed to the adjacent receptacles, said end bars having lugs 30 extending inwardly toward each other and between said receptacles, said cross bars having seats receiving said lugs and flanges abutting the end bars and fixed thereto.

4. In a multiple pan, the combination of a 35 plurality of spaced receptacles with end bars and cross bars connected to said receptacles and secured to each other in face to face relationship, said end bars having downwardly extended lugs at their lower edges between the receptacles. 40

5. In a multiple pan, the combination of a plurality of spaced receptacles with end bars and cross bars connected to said receptacles and to each other, said end bars comprising sheet metal strips folded to provide a double thickness with 45 one layer projecting above the other and having integrally formed lugs on its projecting portion connected with the cross bars in face to face engagement and with the receptacles.

6. In a multiple pan, the combination of a 50 plurality of spaced receptacles with end bars and cross bars connected to said receptacles and to each other, said end bars comprising sheet metal strips folded to produce double thicknesses with the inner ply projecting above the outer ply, said 55 inner ply being cut to permit integrally formed lugs to be bent out of the plane of the ply at its upper edge portion and the two plies being secured together in substantially parallel relation to each other by the upper edge of one of the plies being bent over and about the upper edge 60 of the other.

7. In a multiple pan, the combination of a plurality of spaced receptacles with end bars and cross bars connected to said receptacles and to each other, said cross bars comprising end to 65 end rectangular frames having their adjacent ends connected and their sides fixed to the adjacent receptacles, said end bars having downwardly extended lugs at their lower edges between the receptacles opposite the ends of said rectangular frames whereby said lugs are held at both side edges by said frames against spreading movement with respect to each other longitudinally of the receptacles. 70

8. In a multiple pan, the combination of a 75

plurality of spaced receptacles with end bars and cross bars connected to said receptacles and to each other, said cross bars comprising rectangular frames having end portions fixed to the end bars.

5. In a multiple pan, the combination of a plurality of spaced receptacles with end bars and cross bars connected to said receptacles and to each other, said end bars having lugs extending 10 inwardly toward each other and between said receptacles, said cross bars having seats receiving said lugs into face to face engagement therewith with the end and bottom faces of the lugs in snug engagement with the corresponding edge

portions of the seats so as strongly to reinforce the structure against angular movement of the end bar with respect to the receptacles.

10. In a multiple pan, the combination of a plurality of spaced receptacles with end bars and cross bars connected to said receptacles and to each other, said cross bars comprising rectangular frames having end portions fixed to the end bars, said end bars having lugs extending inwardly in overlapping relationship with the sides 10 of said frames and said receptacles having their top edge portions rolled around the upper edge portions of said lugs, said sides and said end bars.
